SWIVEL RING BINDER

Alfred R. Russell, Grosse Pointe, Mich., assignor
to The Burkhardt Company, Detroit, Mich., a
corporation of Michigan

Application May 29, 1944, Serial No. 537,796

1 Claim. (Cl. 129—1)

1

This invention relates to that class of articles known as swivel ring binders and has for its principal object the provision of a device of this type that is simple in construction, economical to manufacture, and is efficient in use.

Objects of the invention include the provision of a ring binder device comprising a plate member and a so-called ring member which may be made of either metal or suitable non-metallic material such as plastic and which, when made from the latter material offers certain advantages not possible in similar constructions heretofore proposed; the provision of a ring type binder device in which the plate member is formed from a transparent plastic material; the provision of a device of the type described in which at least one edge of the plate member is provided with a reversely bent portion having slots opening transversely onto the free edge of the same, together with a ring member or its equivalent operatively engaged with the opposite side of the plate member and having a notched end portion arranged for removable reception and locking in the notched edge of the plate member; the provision of a construction as above described in which both edges of the plate member are reversely bent and notched and the cooperating ring members are complementarily notched at their opposite ends for removable reception in the notched edges of the plate member; the provision of a construction as above described in which the ring members are resilient and of a dimension between their free ends in excess of the dimension between the reversely turned free edge portions of the plate member whereby the ring members are required to be sprung within the limits of their elasticity to permit complete interengagement thereof with the plate members; the provision of a construction as above described in which the ends of the ring members are provided with beveled faces providing cams for interengagement with the corresponding reversely turned edges of the plate member whereby a force exerted between the end of a ring member and the cooperating free edge of the plate member serves to spring the ring member sufficiently to permit its interengagement with the plate member and upon engagement prevents inadvertent disengagement of the two; the provision of a construction as above described in which the op-

2

positely turned edges of the plate member conform to arcs of a circle so that the ring members may pivot at either end thereon, thus enabling the ring members to be opened up from either side of the plate member; and the provision of a construction as above described in which the reversely turned opposite side edges of the plate member are of arcuate cross-sectional conformation and the cooperating slots in the ends of the ring members are curved for complementary reception of such reversely turned side edges when received in the corresponding slots thereof.

Further objects of the invention comprise a ring type binder and a book or pamphlet maintained in assembled relationship by means thereof, together with identifying means for the book or pamphlet protected by, but visible through, the plate member of the binder; the provision of a construction as above described in which the identifying means for the pamphlet or book comprises a cover member therefor and identifying means printed or otherwise applied to the bound edge of the book or pamphlet; and the provision of a construction as above described in which the identifying means for the book or pamphlet consists of a strip of material separate from the book or pamphlet and inserted between the oppositely turned edges of the plate member of the binder.

The above being among the objects of the present invention the same consists in certain novel features of construction, materials employed in conjunction therewith, and combinations of parts to be hereinafter described with reference to the accompanying drawings, and then claimed, having the above and other objects in view.

In the accompanying drawings which illustrate suitable embodiments of the present invention and in which like numerals refer to like parts throughout the several different views,

Fig. 1 is a fragmentary, perspective view of a swivel ring type binder device constructed in accordance with the present invention and illustrating both ends of the ring in operative engagement with the plate member;

Fig. 2 is a view similar to Fig. 1 but illustrating one end of the ring disengaged from the plate member and the ring member swiveled about the opposite edge of the plate member;

Fig. 3 is a view similar to Fig. 2 but illustrating the ring member as swiveling on the plate member about its opposite edge;

Fig. 4 is an end view of the construction shown in the preceding views showing both ends of the ring member operatively engaged with the plate member in full lines, illustrating the ring member by dot and dash lines in one position corresponding to the position thereof shown in Fig. 2, and in another position thereof the relative position which one end of the ring member preferably assumes when in free and unstressed condition and the opposite end thereof is operatively engaged with the corresponding edge of the plate member;

Fig. 5 is an enlarged fragmentary view of that portion of the construction shown in Fig. 4 within the dot and dash circle 5 thereof, this to bring out more clearly the shape of the slots which are provided in the ring members for cooperative engagement with the arcuately sectioned reversely bent edge portions of the plate members;

Fig. 6 is a fragmentary, perspective view illustrating a notched edge portion of the plate member and the cooperating notched end of the ring member, in exploded view, to better bring out the relative conformation of these parts;

Fig. 7 is a fragmentary, side elevational view of the plate member, and a cooperating ring member, in exploded view;

Fig. 8 is a view similar to Fig. 6 but illustrating a ring member of rectangular cross-sectional conformation;

Fig. 9 is a view similar to Fig. 4 but illustrating an oval type of ring member cooperating with the plate member instead of the partially circular type shown in the preceding views;

Fig. 10 is a fragmentary, perspective view of a construction such as shown in Figs. 1 to 7, inclusive, including a single plate member and a plurality of ring members, applied to the inside of a cooperating cover member;

Fig. 11 is a view similar to Fig. 10 but illustrating a construction in which a plurality of plate members, each with its individual ring member, are employed in place of the continuous plate member shown in Fig. 10;

Fig. 12 is a fragmentary, perspective view of a swivel ring type binder of the type shown in the preceding views securing a plurality of loose leaves together in book-like form and with a title therefor applied to a strip of paper or other flexible material and inserted within the plate member between the opposite reversely turned free edges thereof;

Fig. 13 is a view similar to Fig. 12 but illustrating additionally the use of loose leaf cover members;

Fig. 14 is a view similar to Figs. 12 and 13 but illustrating a construction in which the loose leaves are provided with a single piece cover member which itself carries the title and which is visible through the transparent plate member;

Fig. 15 is a view similar to Fig. 14 but in which the title is applied to the plate member itself;

Fig. 16 is a view similar to Fig. 15 showing the same type of construction but in which the title is placed on a separate strip of flexible material and inserted between the end of the cover and the plate member and is visible through the latter;

Fig. 17 is an enlarged fragmentary, sectional view taken on the line 17—17 of Fig. 16; and

Fig. 18 is a fragmentary, perspective view illus-

trating a modified form of plate and cooperating ring members.

The present invention relates to those types of binders conventionally known as swivel type ring binders. While in the broader aspects of the invention both or either the plate member and the ring members may be formed from metal, the construction is particularly applicable to be formed from non-metallic materials such as any one of a variety of plastic materials now found on the market. This latter feature is particularly desirable at the present time not only because it enables the manufacture of this type of binder made from non-critical material, but because when constructed from transparent plastic it provides advantages not possible when formed from metal. For this reason, in the following description, unless otherwise specified, it will be assumed that both the plate member and the ring members are formed from plastic material, the plate member in particular from a transparent plastic, and those skilled in the art will thereby be able to recognize therefrom the manner in which the construction may also be formed in whole or in part from metal or other suitable material.

Referring now to Fig. 1 it will be noted therefrom that the device of the present invention comprises a plate member 20 which, except for the edge portions thereof, may be formed of any desired cross-sectional configuration but which ordinarily will be desirably formed to a slightly curved conformation as shown. The opposite edges of the plate members 20 are reversely bent or formed as at 22 to present a pair of channel-like elements on the same side of the plate member 20 arranged in opposed relation with respect to each other. The reversely bent edge portions 22 are each of arcuate or partially circular cross-sectional conformation as shown.

For reception of each ring to be carried by a plate member 20 the free edge portion of each reversely bent edge portion 22 is provided with a transverse slot 24 opening onto the free edge thereof, each pair of cooperating slots 24 being aligned with each other transversely of the length of the plate member 20.

Each plate member 20 may be formed for cooperative engagement with one or more ring members. These ring members may be of any desired shape or contour as, for instance, partially circular as illustrated at 26 in Figs. 1 to 7, inclusive, or of partially oval form as illustrated in Fig. 9 at 26a, or otherwise. Furthermore, they may be of any desired cross-sectional configuration such as round as illustrated in Figs. 1 to 7, inclusive, and Fig. 9; square or rectangular as illustrated at 26b in Fig. 8, or of any other conformation. In any event these ring members are of the split type and their free end portions are formed for cooperative engagement with the reversely bent edge portions 22 of the plate member 20.

In order to effect such cooperative engagement of the ring members 26 and plate member 20 each free end portion of the ring members 26 is provided with a pair of transversely aligned notches 28 in the opposite side faces thereof, the notches being of such depth that the thickness remaining in this portion of the ring between the notches 28 is capable of being closely but slidably received between the opposite side walls of the cooperating notches 24. Additionally, and this is important, the notches 28 in side view, as best brought out in Fig. 5, are curved in side elevational view of the

ring in complementary relation with respect to the cross-sectional curvature of the reversely turned side edges 22 of the plate 20, and the width of the notches 28 are substantially equal to the thickness of the material from which the plate member 20 is formed, so that when a ring member and a plate member are in cooperative engagement with one another both the bottom and side walls of the notches or grooves 28 relatively closely but slidably embrace the marginal wall portions of the corresponding reversely turned edge portion 22 at opposite sides of the corresponding notch 24. As a result of this feature when one end only of a ring member, such as 26, is operatively engaged with the reversely bent edge portion 22 of a cooperating plate member 20, the ring as a whole, and as illustrated in Figs. 2 and 3, may pivot about the corresponding reversely turned edge portion 22 of the plate member 20 as shown, the axis of such pivotal movement being, of course, the center of cross-sectional curvature of the corresponding edge portion 22. Furthermore, and as illustrated in Figs. 2 and 3, depending upon which end of the ring member is operatively engaged with the plate member 20, the ring member 26 may swivel with relation to either one side or the other side of the plate member 20 as selected by the user in each case.

The ring members 26 are made of such cross-sectional size in relation to their diameter or other maximum dimensions and to the material from which they are formed as to render them readily flexible under manual pressure to that extent necessary to effect the purposes of the present invention. In other words, it will be appreciated that one end of a ring member may be engaged in the corresponding slot 24 of a plate member without necessarily deforming the ring member 26, but in such case if the spacing of the free end portions of a ring member 26 is such as to conform to its position when fully engaged by the plate member 20, when it will be necessary, after one end of a ring member is engaged with the plate member, as, for instance, as illustrated in Figs. 2 and 3, to spring the remaining end of the ring member towards the first end so that it may pass downwardly within the cooperating end 22 of the plate member in order to enable it to be brought into cooperative relation with respect to its corresponding notch 24. In this respect it is preferable that the free end portions of the ring members 26, etc. when such ring members are in free and unstressed condition, are spaced from each other by an amount slightly greater than the spacing existing when they are both cooperatively engaged in the reversely bent end portions 22 of the cooperating plate member 20. This feature is brought out in the righthand dotted lines in Fig. 4 and is desirable in that it aids in maintaining a tight and secure joint between the ring members and the plate member in service and aids in preventing inadvertent disengagement of the ring members and their cooperating plate member.

Additionally, and as perhaps best brought out in Fig. 5 the extreme end portions of the ring members 26 are preferably so shaped that when both ends of a ring member are operatively engaged in a plate member they substantially contact the inner wall of the central portion of the plate member inwardly of the curved edge portions 22. The mutual inter-engagement of the ring members and plate members in such case act to reinforce one another and stiffen the structure in general.

Another effect of forming the ends of the ring

as above described is that, and as will be particularly appreciated from an inspection of Fig. 4, that in so forming the ends of the rings 26 each end surface forms, in effect, a cam surface. The result of this is that when one end of a ring is operatively engaged with its corresponding side 22 of a plate 20 and the ring is pivoted downwardly to bring the remaining end thereof into engagement with its corresponding side 22, as soon as the ring has been sprung sufficiently to bring the tip end of such remaining end of the ring over the inner margin of its corresponding side 22, a simple downward pressure on the ring member will, because of the cam-like engagement of such yet disconnected end of the ring with its edge 22, cause such end to be cammed inwardly until it passes downwardly beyond such edge and into cooperative engagement therewith.

It will be appreciated from the foregoing that the ring members thus described are releasably engageable with the plate member at both side edges of the latter and may be pivoted or swiveled with respect to the plate member along either edge thereof. This latter feature is of particular advantage in that in no case is it ever necessary to remove more than half of the sheets which are mounted on the rings in order to remove any one sheet, or to add an additional sheet or sheets thereto regardless of the position in which they are to be added. It is also of advantage in that there is no permanent connection between the rings and the plate, they may be sold and shipped in disassembled relationship and readily assembled by the purchaser, and that breakage of one or more rings does not destroy the utility of the device as any such broken rings may be readily and quickly replaced without the necessity of employing skilled help.

The construction described lends itself to application to a relatively wide variety of loose leaf binders. For instance, and as illustrated in Fig. 10 a plate member 20 of a length equivalent to the length of a flexible or other cover member 30 may be provided with two or more ring members 26 arranged in suitable or desirably spaced relation along the length of the same and suitably secured to the inside of the cover 30 by any suitable means such as rivets 32.

On the other hand and as illustrated in Fig. 11, instead of providing a plate member 20 of a length equivalent to the length of the cover member 30, a plurality of shorter plate sections 20 may be employed, each with one or more ring members 26 cooperating therewith, the plate members 20 being arranged in end-to-end relationship within the cover 30 and each suitably secured thereto as, for instance, by means of rivets 34.

In the constructions illustrated in Figs. 10 and 11 the plate members 20 may obviously be formed of either metal or other suitable non-metallic material such as plastic or the like without affecting the results obtained thereby in either one way or another.

However, if the plate member 20 is formed from a plastic material, then advantages result which are not possible where the plate members are formed of metal. For instance, and as illustrated in Fig. 12, in which case it is assumed that the plate member 20 is formed from a transparent plastic material, it is assumed that a plurality of loose leaves, indicated generally at 36, are mounted upon the rings 26 and relate to a particular subject. In such case a strip 38 of flexible material of suitable character and which

ordinarily will be a strip of paper, may have a title such as 40 printed or otherwise applied thereto and the strip 38 simply inserted between the reversely bent marginal edge portions of the plate 20 with the title facing outwardly so as to be visible through the transparent plate 20 as shown. The strip 38 in such case is, of course, preferably of such width that when inserted between the oppositely bent edges 22 of the plate 20 it will be frictionally held in position therein. Thus the title may be readily applied and/or replaced and is protected against disfigurement by the plate 20.

Where heavier sides for a book or pamphlet such as illustrated in Fig. 12 is desired, then as illustrated in Fig. 13 heavier and either stiff or flexible separate cover members 42 may simply be slipped on the rings 26 outwardly of the loose leaf 36 to provide the desired structure.

On the other hand and as brought out in Fig. 14 a one-piece cover such as 44 may be desired for the loose leaves 36 in which case the cover 44 may be suitably scored for bending into complementary cross-sectional configuration for reception within the plate 20 between the reversely turned marginal side edge portions 22 thereof as shown in Fig. 14, and applied to the rings 26 along with the loose leaf sheets 36. In this case if a title 40 is desired it may, of course, be printed on the edge of the cover 44 in which case it will be visible through the transparent plate 20 in the same manner as the constructions heretofore described.

It is not, of course, necessary to apply a title to a pamphlet or book assembly of the type described on a strip of paper such as 38 or on the end wall of a cover such as 44 so as to be visible through the transparent plate member 20 and, of course, where the plate member 20 is not transparent, then, of course, such method of applying the title to the book is useless in any case. In any case and if desired a title such as 50 may, of course, be applied to the outer surface of the plate member 20 as illustrated in Fig. 15 which illustrates the same construction as in Fig. 14 except for this one feature.

It will likewise be appreciated that even where a construction as illustrated in Figs. 14 and 15 is used, that is one in which the cover member 44 of one-piece construction, and the plate member 20 is of transparent material, the same separate strip of material 38 carrying the title 40 as employed in the construction shown in Figs. 12 and 13 may be employed if desired.

In the broader aspects of the invention, that is the feature employing a notched edge for the plate member and a cooperating notched end on the ring members arranged for releasably interlocking engagement with one another and in which the ring members are manually distortable to permit engagement and disengagement of a free end thereof with the plate member, then it is not necessary that both ends of the ring members releasably cooperate with the plate member although this is ordinarily desirable and is believed to involve invention over a construction which has only one end of the ring member so engageable with the plate member. In other words, in the broader aspects of the invention a plate member such as 20a illustrated in Fig. 18 may be employed and provided with only one reversely bent marginal edge portion such as 21. The ring members here illustrated at 27 may be permanently secured at one end to that marginal edge portion of the plate member 20a opposite

the edge 21 thereof and may, in fact, and as illustrated in Fig. 18, be formed integrally therewith if desired. The reversely turned edge portion 21 in such case will be provided with transverse notches 24a in alignment transversely of the length of the plate member 20a with the points of connection of the corresponding ring members 27 thereto, and the free end portions of the ring members 27 in such case will be provided in their opposite side edges with opposed and aligned notches 28a, corresponding with the notches 28 in the rings previously described, for cooperative engagement with the corresponding notches 24a. This type of construction will be found to be more practical when constructed of relatively flexible material such as thin spring metal, relatively thinner plastic material than that which will ordinarily be found advisable in the constructions first described, or it may be even made of a good grade of fibre board of suitable thickness and character. In this case it is, of course, not necessary that the reversely turned edge portion 21 of the plate member 20a conform closely in cross-sectional configuration to the arc of a circle but it is preferable that the ring members 27, when in free and unstressed condition, are arranged with their free end portion positioned laterally outwardly of the bottoms of the notches 24a so that the natural spring of the material from which they are formed will tend to hold them securely in the notches 24 when operatively engaged with the walls thereof.

Having thus described my invention, what I claim by Letters Patent is:

In a swivel ring type binder, in combination, a plate member, reversely bent side edge portions on said plate member providing a pair of opposed and spaced channels each of partially circular cross-sectional configuration, said reversely turned side edge portions having transversely disposed notches opening onto the free edges thereof and said notches being aligned with each other transversely of the length of the said plate member, a flexible split ring member distortable under manual pressure and within the elastic limits of the material thereof to vary the distance between the free ends thereof, each free end portion of said ring member being provided with a slot in each side thereof, said slots being arranged in opposed relation with respect to each other and the slots in each of said free end portions being spaced from one another by a distance substantially equal to the width of said transversely disposed notches in said reversely bent side edge portions, said slots in side elevation being curved into conformance with the cross-sectional curvature of said reversely bent side edge portions and being of a width substantially equal to the thickness of the material of said reversely bent side edge portions whereby said free end portions may be removably received in the notched portions of said reversely bent side edge portions of said plate member and said ring member may pivot about either of said reversely bent side edge portions of said plate member when the opposite end thereof is disengaged from its correspondingly reversely bent side edge portions, the ends of said ring member providing cam surfaces engageable with the corresponding free edge portions of said reversely bent side edge portions of said plate member to force the free ends of said ring member toward one another upon pressure applied to said ring member during assembly to said plate member in a direction perpendicular

to the general plane of thickness of said plate member and in a direction towards the latter.

ALFRED R. RUSSELL.
